UNITED STATES PATENT OFFICE.

OTTO WIDMAIER, OF LEIPZIG, GERMANY.

APPARATUS FOR ENVELOPING LETTERS AND THE LIKE.

1,120,576.

Specification of Letters Patent.

Patented Dec. 8, 1914.

Application filed August 28, 1913. Serial No. 787,090.

To all whom it may concern:

Be it known that I, OTTO WIDMAIER, manufacturer, a subject of the Emperor of Germany, residing at No. 6 Beuchaerstrasse, 5 Leipzig, Saxony, Germany, have invented certain new and useful Improvements in Apparatus for Enveloping Letters and the like, of which the following is a specification.

10 The present method of enveloping letters and the like consists in folding up the letter, placing it in the envelop and sealing the latter.

15 The object of the present invention is to effect these three operations in one single operation by mechanical means. This object is attained according to the invention by folding a sheet of paper and the note paper simultaneously so that the former forms the 20 envelop which is then sealed.

In the accompanying drawings,—Figure 1 illustrates an envelop-sheet with its associated letter-sheet in one stage of its folding process; Fig. 2 is a view similar to Fig. 1, 25 the letter-sheet having been folded upon itself once; Fig. 3 illustrates the letter as finally folded by the machine of the present invention; Fig. 4 is a side view, partly in section, of the preferred form of machine; 30 Fig. 5 is a plan view of the machine illustrated in Fig. 4; Fig. 6 is an end view, partly in section, of the machine illustrated in Figs. 4 and 5; and Fig. 7 is a plan view 35 of a preferred form of sheet-supporting bed or table.

In Figs. 1-3, 62 designates the envelop paper and 63 the letter placed thereon. The envelop paper in this case only projects beyond the letter at three sides (Fig. 1), the 40 note-paper projecting beyond one side of the envelop paper. In enveloping, the letter is first of all folded on the line A—B, so that the associated sheets have the appearance shown at Fig. 2, whereby two flaps on 45 the left hand side of the envelop paper engage over the once folded letter. After the moistening operation, the letter and envelop are folded on the line C—D, this concluding the enveloping process (see Fig. 3). 50 The machine for this purpose comprises the frame 1, which is partly covered by the plate 2 screwed to the frame. The plate 2 is provided with a slot 3 disposed transversely to the machine, the edges of the 55 walls of said slot being bent downward. Underneath the slot, and arranged parallel

thereto, are two rollers 4 and 5 mounted on the frame 1, the roller 5 being adjustable and pressed toward the roller 4 by a spring 6, the compression of which can be regulated.

Mounted in the opposite side of the frame parallel to the other rollers 4, 5, is a third roller 7, which is connected to the roller 5 by conveyer bands 8, and is disposed at 65 such a height that the bands 8 passing around the roller 5, underneath the roller 4 to roller 7 and returning from the latter to roller 9 have a travel substantially horizontal from one end of the machine to the 70 other. In order to provide the conveyer bands with the requisite tension weighted jockey pulleys 9 are provided. Arranged above the slot 3, and adapted to coöperate therewith, is a fold blade 10, which is fixed 75 to an arm 11 extending over the plate 2. This arm 11 is mounted on a shaft 12 journaled in the frame 1 parallel to the rollers 4 and 5. Keyed to the same shaft 12 through a sleeve 46' is a lever 13 provided 80 with a roller 14, which coacts with a cam 15 and serves to impart an intermittent rocking movement to the arm 11. The cam 15 is mounted on a shaft 16 likewise mounted in the frame 1 parallel to the shaft 12, said 85 shaft 16 being driven by the main shaft 21 through gears 17, 18, 19, 20. The gears 18 and 19 are mounted above the main shaft 21, and the gear 19 also meshes with the gear 22 on the shaft of the roller 4, said 90 gear 22 meshing with the gear 23 on the shaft of the roller 5. By this means the rollers 4 and 5 are also driven from the main shaft 21.

At the side of the plate 2, and close up to 95 the underside of the upper travel of the conveyer bands 8, is another plate 24, which has a stop 25 projecting between the bands 8 and is provided with a slot 26 similar to the slot 3 but disposed at right angles to the latter. Underneath the slot 26 and parallel thereto are two rollers 27, 28, the roller 27 being driven through gears 30, 29, by the shaft 31 mounted at right angles to the main shaft 21; while the roller 28 is 100 driven by the roller 27 by friction.

The shafts 31 and 21 are connected by bevel gearing 32, 33. Extending down from the underside of the rollers 27, 28 to another pair of rollers 35, 36 is an inclined 110 plane 34, while a depositing plate 37 arranged substantially in the same plane as

the plane 34 passes downward from the rollers 35, 36. The roller 35 is likewise driven from the shaft 31 by gears 38, 39, 40 and 30, and the roller 36 is friction driven.

5 Arranged above the plate 24 is a gumming or moistening device 41, which is rectilinearly guided by its pins 42 in a double arm 43 fixed to the frame 1, so that the lower edge of the gumming device moves up 10 and down parallel to the plate 24. This reciprocating movement is imparted to the device 41 by an arm 44 and link 45. The arm 44 is pivoted through its sleeve 46 upon the shaft 12, and is intermittently raised 15 and lowered by an arm 47 connected to the sleeve 46 and provided with a roller 49, which coöperates with the cam 48 on the shaft 16. A fold blade 50, carried by an arm 51, coöperates with the slot 26. The 20 arm 51 is keyed to a shaft 52 journaled in the frame 1, said shaft having another arm 53, which carries a roller 54 which coöperates with a cam 55 on the shaft 16, thereby imparting an intermittent rocking movement to the arm 51. The latter is provided 25 with two depending extensions 56 which are pivoted to two catching arms 57, the latter being guided on the frame 1. The ends 58 of said arms project through openings 59 in the inclined plane 34 when the fold blade 50 is in its raised position, but when the latter is lowered retract from the plane 34.

30 The plate 2 is provided with adjustable angle pieces 60, 61, of which 60 serves as an abutment for the paper sheet 62 serving to form the envelop, and 61 as an abutment for the sheet of note paper 63. Mounted in the corners of the angle pieces 60, 61 are 35 rotating brushes 64, 65, which may be connected in any desired manner to the driving shaft of the machine, and which serve to guide the paper sheets placed in the machine exactly into the position determined 40 by the abutments 60, 61, and to hold them in this position.

45 The operation of the device is as follows:—After the sheet of paper 62 adapted to form the envelop, and the sheet of note paper 63 have been placed on their table, the note paper being placed on top of the envelop sheet, the fold blade 10 operates and folds the sheets along the line A—B, (Fig. 1) by pressing them through the slot 3. The two sheets are then engaged by the rollers 4, 5, and leaving the latter are conveyed by the conveyer bands 8 to the plate 24. Both sheets appear then as shown at Fig. 2, the sheet of note paper lying once 55 folded on the sheet 62, which latter projects on three sides beyond the folded sheet of note paper, while the fourth side provided with the specially formed edge is folded over the sheet of note paper 63. As soon as 60 the two sheets meet the abutment 25 by

which they are held fast, the gumming or moistening device 41 descends and either gums or moistens, according to whether the letter is to be sent by letter or book post, the edges of the sheet 62 being indicated in Fig. 2 by *a*, *b* or by *a*, *b*, and *c*. As soon as this is accomplished, the device 41 rises and the fold knife 50 becomes operative and by pressing both sheets along the line C—D (Fig. 2) into the slot 26 folds them. The 70 sheets are hereby engaged by the pair of rollers 27, 28 and transferred to the inclined plane 34, whereby the pressure of the two rollers presses together the moistened gummed edges. As soon as the envelop 80 which is now in a finished condition and incloses the note paper is released by the rollers 27, 28 it slides down the inclined plane 34 to the catching arms 58, which first of all hold it until the fold blade 50 makes 85 the next fold. When this has been effected, the catching arms withdraw and the finished envelop passes between the rollers 35, 36, which press the envelop again and transfer it to the depositing plate 37. As 90 previously mentioned the device 41 may either be in the form of an adhesive applying device or a moistening device, in the latter case the corresponding edges of the sheet 62 would of course have to be already 95 gummed. According to the manner in which the sheet 62 is gummed, or the manner in which the device 41 applies the adhesive, the envelop will be sealed at all four edges or one side will be open. In the latter 100 case the note paper is prevented from falling out of its envelop by the unsealed edge of the latter and the note paper being folded over.

105 The advantages of the invention will be apparent, inasmuch as it combines two previously separate operations one of which was hitherto performed by machinery and the other by hand, into one operation.

I claim:

110 1. In a machine for folding and enveloping letters, a slotted feed-plate adapted to receive a letter-sheet and its associated envelop-sheet, a pair of feed-rollers disposed beneath said plate, and a folding means comprising a pivoted folding-blade arranged to thrust said letter-sheet with its envelop-sheet through the slit to said rollers; a second slotted feed-plate, the slit of said plate being disposed at right-angles to the plane of the 115 slit of the first plate, a pair of feed-rollers beneath said second plate, a second folding means comprising a folding-blade arranged to thrust the letter-sheet and envelop through the slit of said second feed-plate, a traveling 120 band adapted to transport the letter-sheet and envelop from the first folding-means to the second folding-means, and a vertically 125 movable gum-moistening device above the second feed-plate.

130

2. In a machine for folding and enveloping letters, a primary folding-device, a secondary folding-device arranged at right-angles to the primary folding-device, means 5 for transporting a letter-sheet with its envelop-sheet from said primary folding-device to said secondary folding-device, a gumming device in proximity to said secondary folding-device, a pair of rollers between 10 which the folded envelop with its letter is fed from the secondary folding-device, an inclined chute arranged to convey the enveloped letter from said rollers, and a pair of sealing-rollers near the discharge end of 15 said chute.
3. In a machine for folding and enveloping letters, a primary folding-device, a secondary folding-device arranged at right-angles to said first folding-device, means for 20 transporting a letter-sheet with its envelop-
- sheet from said primary folding-device to said secondary folding-device, a gumming device in proximity to said secondary folding-device, said secondary folding-device including a pair of rollers, a swinging blade 25 adapted to fold the envelop- and letter-sheets and to push the same between said rollers, an inclined chute arranged to convey the enveloped letter from said rollers, a pair of sealing-rollers near the discharge 30 end of said chute, and catch-arms connected to and controlled by said folding-blade and adapted to intercept the enveloped letter before it reaches said sealing-rollers.

In testimony whereof I affix my signature 35
in presence of two witnesses.
